FIG. 1 is a side elevational view of an electrical connector embodying my new design;

FIG. 2 is a rear end elevational view of the connector of FIG. 1 viewed in the direction of the arrow 2 shown in FIG. 1;

FIG. 3 is a rear end elevational view of the connector in FIG. 1 shown in the direction of the arrow 3 shown in FIG. 1;

FIG. 4 is a bottom plan view of the connector shown in FIG. 1;

FIG. 5 is a sectional view of the connector taken on the line 5-5 in FIG. 4.

FIG. 6 is a front end elevational view of the plug insulator shell of the connector of FIG. 1 shown disconnected from the receptacle insulator shell of the connector; and

FIG. 7 is a front end elevational view of the receptacle insulator shell of the connector of FIG. 1 shown disconnected from the plug insulator shell.

The plug insulator shell and receptacle insulator shell are shown as separate parts in FIGS. 6 and 7 for the purpose of completeness of disclosure.

I claim:

The ornamental design for an electrical connector, substantially as shown and described.
